UNITED STATES PATENT OFFICE

156,052

DESIGN FOR A BATHTUB

Juan Springwell, Inverness, Ill., assignor to Sears, Roebuck and Co., Chicago, Ill., a corporation of New York

Application May 26, 1948, Serial No. 146,607

Term of patent 14 years

(Cl. D4—4)

To all whom it may concern:

Be it known that I, Juan Springwell, a citizen of the United States and a resident of Chicago, in the county of Cook and State of Illinois, have invented a new, original, and ornamental Design for a Bathtub, of which the following is a specification, reference being had to the accompanying drawing, forming a part thereof.

Fig. 1 is a perspective view of a bathtub embodying my new design;

Fig. 2 is a top plan view of the same; and

Figs. 3, 4 and 5 are fragmentary sectional views taken substantially along the lines 3—3, 4—4 and 5—5 of Fig. 1.

The back and side not shown are plain.

I claim:

The ornamental design for a bathtub, as shown and described.

JUAN SPRINGWELL.
